UNITED STATES PATENT OFFICE.

HORACE D. STEVENS, OF AKRON, OHIO, ASSIGNOR TO THE FIRESTONE TIRE AND RUBBER COMPANY, OF AKRON, OHIO, A CORPORATION OF OHIO.

VALVE-HOLE-PUNCHING MACHINE FOR INNER TUBES.

Application filed June 12, 1922. Serial No. 567,563.

Prior to this invention it was customary in the manufacture of inner tubes for pneumatic tires, to form the hole, through which the valve stem was inserted, by hand before the ends of the tube were joined or spliced. This operation was performed by two workmen who laid a number of tubes on a table in parallel relation. One of the workmen would insert boards or sticks in the mouth of a tube while the other, with a hand punch and mallet, made the holes in the tube. This primitive method has endured until the introduction of the present invention, the object of which is to produce a machine to punch these valve stem holes in inner tubes, thus speeding up the work and lessening the labor required for the operation.

In the drawings and description accompanying this application is shown one embodiment of the invention, but it will be understood that the showing and description are not to be considered as limiting the scope of the invention beyond the requirements of the prior art and within the substance of the appended claims.

In the drawings:

Figure 1 is a side elevation of the machine;

Figure 2 is an end elevation, a portion of the head being removed;

Figure 3 is a vertical section through the head;

Figure 4 is a sectional view of the punch.

The apparatus comprises a platform or base 1 on which is mounted the motor 2 for driving the apparatus which may be connected to any source of power by flexible cables (not shown). The platform is preferably mounted on casters or rollers 3 so that the apparatus may be moved about the factory to the location of the tubes on which it is intended to operate. This arrangement is advantageous as it does away with trucking the tubes.

From the platform 1 rises a standard or column 4 which is of sufficient height to enable the punching operation to be carried on expeditiously. Near the top of the standard there is arranged a horizontal arm 5, which may be constructed from a hollow piping, and in the outer end of which is carried a removable anvil or work rest 6, usually composed of a hard wood so as to afford a surface against which the cutting tool may operate. The anvil may be re-

placed when worn. The arm 5 is long enough so that the tube may be slipped over it for a considerable distance in order that the valve stem hole may not come too near to the splice.

Above and parallel to the arm 5 is a second arm 7, at a convenient point on which is carried a block 8 which pivotally supports a rocking lever 9, normally held in raised position by a spring 10. To the inner end of the lever 9 is attached a link 11, which extends downward through the platform and is connected at its lower end to a foot treadle 12 pivoted in a hanger 13 depending from the lower side of the platform.

On the end of the arm 7 is carried a stationary head 14 in which is mounted a vertically reciprocable and rotary shaft 15, the upper end of which carries a pulley 16 arranged to be rotated by a belt 17. The belt 17 is driven by the motor 2, being trained over pulleys 18 supported on the upper end of the standard 4.

The outer end of the lever 9 is forked as 18 and engages a loose collar 19 held between collars 20 secured on the upper end of shaft 15. An adjustable pin 21 is carried in the end of the lever 9 being adapted to limit downward movement of the shaft 15 by contacting the upper surface of the head 14.

The lower end of the shaft over the anvil 6 is formed with a screw-threaded socket 22 in which is received a replaceable punch 23, the lower end of which is formed as a cutting edge of the size of the hole to be punched in the tube. The punch or cutting element 23 is hollow so that the disks of rubber may be forced upwardly therein, the upper end of the punch communicating with a recess 24 vented at 25 to the outer surface of the shaft. A deflecting plug or ejector 26, having an inclined surface facing toward opening 25, is located in the recess 24 and serves to direct the cut-out disks toward the opening where they are discharged. A U-shaped stripper plate 27 depends from the head, being provided with an aperture 28 through which the tool is projected, and operates to strip the tube from the cutting tool.

The operation of the apparatus is easily understood. The operator takes a bunch of tubes, the ends of which have not been

spliced, and passes one end over the arm 5 until the anvil 6 is at the point desired for the valve stem hole. He then depresses the treadle 12 forcing the rotating punch into the tube. The operation is much quicker and easier than the old hand punching operation.

Changes and modifications may be made in the apparatus without affecting the essential features of the invention, and such changes as fall within the scope of the invention are intended to be covered by the claims attached hereto.

What I claim is:

- 15 1. An apparatus for punching valve stem holes in inner tubes comprising an elongated arm adapted to receive an inner tube there-over, an imperforate anvil on the end of said arm, a rotary punch above the anvil, and means to depress the punch.
- 20 2. An apparatus for punching valve stem holes in inner tubes comprising an elongated arm adaptable for insertion within the inner tube, an imperforate anvil on the outer end 25 of the arm, a rotary and reciprocable cut-

ting tool above the anvil, and means for rotating and depressing the cutting tool.

3. An apparatus of the character set forth comprising the combination of an elongated arm adaptable for insertion within an inner tube, an anvil on the outer end of said arm, a stationary head above the anvil, a rotary and reciprocable tool in said head said tool being hollow, an ejector above said tool, means for moving said tool longitudinally of the head, and rotary driving means for the tool.

4. In an apparatus for the uses and purposes set forth a movable platform, a standard rising from said platform, parallel arms 40 extending from said standard one of said arms being adaptable to receive an inner tube, a replaceable anvil in the end of said arm, a head on the end of the other arm, a rotary and reciprocable shaft in said head, 45 a lever by which the shaft may be reciprocated, a punch in the end of said shaft over the anvil said punch being hollow, and an ejector at the upper end of said punch.

HORACE D. STEVENS.
